UNITED STATES PATENT OFFICE

2,420,696

SEWING MACHINE

Clarence S. Best, Belvidere, Ill., assignor to
 National Sewing Machine Company, Belvidere,
 Ill., a corporation of Illinois

Application May 21, 1945, Serial No. 594,808

8 Claims. (Cl. 112—210)

1

This invention relates to improvements in sewing machines and particularly to a machine provided with drop feed mechanism and improved means for operating the feed dog to impart thereto the combined rise-and-fall and feed-and-return movements, in a positively defined path, for efficiently feeding the work.

Sewing machines heretofore have been provided with means for producing ordinary sewing, that is, sewing in which the work is moved by the feed dog away from the operator, and for producing reverse sewing, in which the work is moved by the feed dog toward the operator. For certain kinds of work, particularly for darning and mending and the like, it is desirable to manipulate the work back and forth without having to actuate reversing mechanism for alternating the direction of movement of the feed dog. To enable the operator to move the work back and forth freely, as required, without resorting to the use of reversing mechanism, it is necessary to drop the feed dog into inoperative position below the level of the bed plate of the machine. One of the objects of this invention is to produce improved drop feed mechanism for the purpose stated.

Another object of the invention is to provide novel and efficient mechanism for driving the shafts which impart to the feed dog the combined rise-and-fall and push-and-pull motions. As is well understood in the art, the feed dog has imparted to it certain movements in the order stated: rise, push (work-engaging), fall, and pull (below the level of the work), and these cycles of motion may be clockwise or anticlockwise depending on whether the machine is set for ordinary or reverse sewing.

Another important object of my invention is to provide mechanism for moving the feed dog in a rectangular, positively defined path, that is, the feed dog is raised and lowered in different but substantially vertical planes, and is fed and returned in different but substantially horizontal planes. These positively defined motions cause the feed dog to engage the work efficiently and positively and to move in a horizontal plane for each stitch forming operation; and cause the feed dog to disengage the work and to move positively out of the way in preparation for the next stitch forming operation.

In the drawings:

Fig. 1 is an elevational view of a sewing machine embodying my invention.

Fig. 2 is a bottom plan view of the mechanism located under the bed plate of the machine.

Fig. 3 is a transverse, vertical, sectional view taken in the plane of the lines 3—3 on Figs. 1 and 2, looking in the direction indicated by the arrows.

2

Fig. 4 is a bottom plan view of part of the mechanism under the bed plate, particularly the eccentric strap rack, as viewed from the plane of the line 4—4 on Fig. 3.

5 Fig. 5 is a vertical sectional view, partly in elevation, on an enlarged scale, showing the eccentric and clutch mounted on the lower end of the vertical drive shaft.

Fig. 6 is a transverse, vertical sectional view of 10 part of the reversing mechanism, taken in the plane of the line 6—6 on Fig. 1.

Figs. 7 and 8 are diagrammatic views showing 15 the operative connections between the feed shaft and feed dog and between the rise and fall shaft and feed dog, and the successive positions of the feed dog and its operative connections during the rise, push, fall and pull motions of the feed dog.

Fig. 9 is an elevational view of a part of the 20 reversing mechanism and its connection to the feed shaft.

Figs. 10 and 11 are diagrammatic views showing 25 two positions of the slotted reversing bracket and the roller movable therein, and illustrating the effect thereof on the feed shaft.

25 Conventional parts of the sewing machine shown in Fig. 1 include the bed plate 20, upright standard 21, overhanging arm 22, sewing head 23 and presser foot 24. The main drive shaft 25 extends horizontally through the overhanging arm 22. It may be motor driven or treadle operated, as is well understood in the art.

Referring more particularly to that embodiment of my invention which I have chosen to illustrate in the drawings, the main drive shaft 25, through the gears 26, 27, drives the rotatable vertical shaft 28 located in the upright standard 21 (Figs. 3 and 5) for actuating the rise and fall shaft 29 located beneath the bed plate of the machine. To the right of said shaft 28 is the vertical connecting rod 30 which is reciprocated by the eccentric 31 mounted on the horizontal shaft 25 (Figs. 1 and 2) for actuating the feed shaft 32.

The vertical shaft 28 has connected to its lower 45 end a beveled gear 33 which meshes with the beveled gear 34 fixed on the end of the hook shaft 35 which is mounted in bearings 36 under the bed plate 20. The hook shaft 35 has fixed on its free end the hook or loop taker, indicated as a whole at 37. The hook shaft 35 is rotated continuously 50 in one direction by the rotatable shaft 28 so that the hook 37 will cooperate with the needle operating mechanism in the head in the stitch forming operation.

55 The vertical shaft 28 also actuates the rise and fall shaft 29. Said shaft 28 is connected to the shaft 29 through the following described mechanism: an integrally formed eccentric 38 and concentric clutch 39 are slidably mounted on the 60 lower end of the shaft 28; the eccentric 38 and

clutch 39 are spaced from each other by an annular recess 40; a pin 41 extends upwardly from the clutch through the recess 40 to a point opposite the low side of the eccentric 38 (Fig. 5). A pin 42 is fixed horizontally in the lower end of the shaft 28 and extends into an annular recess 43 between the shaft 28 and clutch 39. When the clutch is in a predetermined position, the pin 42 is adapted to enter a notch 44 formed internally in the clutch 39, as will be explained in the description of the operation of the machine.

An eccentric strap rack 45 is slotted at 46 and mounted on a headed bolt 47 which extends through the slot 46 into a fixed part of the machine beneath the bed plate 20 (Fig. 4). The strap rack 45 has a toothed rack 48 at its free end, and intermediate its ends is provided with a square opening 49 adapted to receive the eccentric 38 on shaft 28. The depending teeth of the rack 48 of the strap 45 engage the teeth 50 of the toothed segment 51 which is fixed on the rise and fall shaft 29 by a set screw 52.

To insure keeping the rack teeth 48 in engagement with the teeth 50 of the segment 51, I have provided a retaining lever 53 which is pivotally mounted on a pin 54 in a bracket 55 fixedly connected to the under side of the bed plate 20. An adjusting screw, shown but not numbered, extends through the lever 53 near the pivotal mounting 54 and is engageable with the bed plate. The free end of the lever 53 has roller retaining fingers 56 for holding the roller 57 between them and in position for bearing on the rack 48 (Figs. 3 and 4).

The eccentric 38 and clutch 39, as a unit, are slidably mounted on the shaft 28 and are manually actuated by means of the plunger 58 provided with a control button 59 located above the bed plate 20, the plunger 58 being bent at right angles and connected at 60 to a clutch engaging fork indicated as a whole at 61. The fork 61 is pivotally mounted by a bolt or screw 62 on a fixed part 63 of the bed plate of the machine. The free end of the fork is provided with spaced apart arms 64, 64, adapted to engage the clutch 39 as best shown in Figs. 2 and 3.

Referring now to the operative connections between the rise and fall shaft 29, the feed shaft 32, and the feed dog 65, reference to Figs. 2, 7 and 8 will show that the feed shaft 32 has fixedly mounted on it a link 66 to which is pivotally connected the feed block rocker 67. The rise and fall shaft 29 has fixedly mounted on it a link 68 pivotally connected at 69 to the link 70, and the latter is pivotally connected at 71 to the arm 72 of the feed block rocker 67. The rocker 67 is rigidly connected through the arm 73 to the feed dog 65.

The opposite end of the feed shaft 32 is operatively connected to the connecting rod 30 by the mechanism best shown in Figs. 2, 6 and 9, namely: the rocker arm 74, pivotally connected by the pin 75 to the link 76 on which is rotatably mounted a roller 77 which is movable in the slot 78 of the reversing bracket 79. Said bracket 79 is pivotally secured to a fixed part of the upright standard as indicated at 80 in Fig. 1. An arm 81 which extends rigidly from the bracket 79 is pivotally connected to the control lever 82 by means of which the position of the bracket 79 and its slot 78 is adjusted.

Bearing blocks 83, 84, bored to receive the shafts 29 and 32, are rigidly mounted on or cast with the bed plate 21.

Operation.—The vertical shaft 28 rotates continuously when power has been applied to the

main drive shaft 25, and therefore continuously rotates the hook shaft 35, as heretofore explained. Said main drive shaft 25, through the eccentric 31 and connecting rod 30, continuously imparts rocking motion to the feed shaft 32. The shaft 32, through its operative connections with the feed dog 65, thus constantly imparts reciprocating feed and return motions to the feed dog 65. For ordinary sewing, these push and pull motions take place in different horizontal planes through the reciprocating rocking motion of the rise and fall shaft 29, whereas for special work such as mending, darning and the like, these push and pull motions are made to take place in a single horizontal plane below the level of the bed plate, by holding the feed dog in dropped position by means of the drop feed mechanism.

Said drop feed mechanism operates through the eccentric-clutch unit best shown in Figs. 3, 4 and 5. When the plunger 58 and fork 61 have been actuated to lift the eccentric 38 and clutch 39 to the position shown in said figures, the drive pin 42 will be out of engagement with the notch 44, and the vertical lock pin 41 will extend into the square slot 49 of the strap rack 45. The shaft 28 in its continuous rotation will carry the eccentric 38 and clutch 39 only to the position shown in Fig. 4, wherein the lock pin 41 prevents rotation of the eccentric 38. While the eccentric is idle, the strap rack 45 and toothed segment 51 remain stationary also, and the rise and fall shaft 29 becomes inoperative. In this position of the eccentric-clutch unit, the rise and fall shaft 29 and the connections between said shaft and the feed dog 65 hold said feed dog in its lowered or "fall" position, out of engagement with the work, and consequently the rocking movement of the feed shaft 32 results in reciprocating the feed dog 65 in one horizontal plane, below the level of the bed plate, as indicated in Fig. 8.

When the plunger 58 and fork 61 have been actuated to lower the eccentric 38 and clutch 39 relatively to the shaft 28, the drive pin 42 will engage the notch 44 and drivingly connect the clutch unit 38—39 to the shaft 28, and the lock pin 41 will be lowered with the unit to a position where it cannot interfere with the rotation of the eccentric 38. Now the rotation of the shaft 28 results in rotation of the eccentric 38 and consequent reciprocation of the strap rack 45, which in turn rocks the segment 51 and the rise and fall shaft 29.

In this position of the eccentric 38, the rise and fall shaft 29 and the connections between said shaft and the feed dog 65 impart to said feed dog the alternating rise and fall movements, and consequently the rocking movement of the feed shaft 32 combined with the rise and fall movements imparted by the shaft 29, result in reciprocating the feed dog 65 in two different horizontal planes, namely, in one direction in the raised, work-engaging plane, and in the opposite direction in the lowered, non-work-engaging plane.

Another element enters into the operation of the above described parts, namely, the control of the direction of movement of the feed dog when it is in the raised work-engaging position. This is controlled by the reversing mechanism (Figs. 1, 6, 9, 10 and 11), the adjusted position of which establishes the timing relationship between the operation of the rise and fall shaft 29 and the feed shaft 32, and determines whether the feed dog is to move away from or toward the

operator when in its raised or "push" stroke. The path traveled by the feed dog 65 in this embodiment of my invention may be likened to a rectangular path starting at 8 on the face of a clock, rising to 10, moving horizontally to the right to 2, down to 4, and then horizontally to the left to 8. The direction of movement over this path may be clockwise or anti-clockwise.

As shown in Fig. 7, the movement of the feed dog is in the anti-clockwise direction; that is, from the solid line to the dotted line position, toward the operator, as in reverse sewing. Using the illustration above stated, the movement is from 2 on the face of a clock toward the left to 10, in Figure 7; then down to 8 and to the right across to 4, as in Fig. 8.

Fig. 10 shows diagrammatically the position of the reversing bracket 19 and the rocked position of the feed shaft 32 when the feed dog 65 is intended to be moved from right to left on its raised or "push" stroke, as in Fig. 7. Fig. 11 shows diagrammatically the position of the reversing bracket 19 and of the rocked feed shaft 32 when the feed dog is intended to be moved in the opposite direction, from left to right, on its raised or "push" stroke.

It will be understood that while the reversing mechanism functions to control the direction of movement of the feed dog, which is essential to the control of ordinary and reverse sewing, said reversing mechanism may be in either position without affecting the operation of the machine for "drop feed" work. Obviously, when the feed dog 65 is held in dropped position by means of the plunger 58, fork 61, clutch 39, eccentric 38, strap rack 45, segment 51 and rise and fall shaft 29, the horizontal reciprocation of the feed dog imparted by the feed shaft 32 takes place in one single horizontal plane below the level of the bed plate, where the dog cannot engage the work, and therefore the operator is enabled to move the work manually as desired.

Changes may be made in details of construction and form of parts without departing from the scope of my invention as set forth in the appended claims.

I claim:

1. A sewing machine comprising a bed plate, a feed dog movably mounted therein, a horizontal power shaft rotatably mounted above the bed plate, a rotatable vertical shaft driven by the power shaft, a reciprocating connecting rod also driven by the power shaft, a rotatable horizontal hook shaft journaled under the bed plate and geared to said vertical shaft, a feed dog lifter rock shaft operatively connected to the feed dog for imparting rise and fall motions to the feed dog, a feed rock shaft operatively connected to the feed dog for imparting feed and return motions to the feed dog, said lifter and feed rock shafts being journaled under the bed plate parallel with the hook shaft, operative connections between the feed rock shaft and said reciprocating connecting rod for imparting continuous rocking motion to said feed shaft, and operative connections between said lifter rock shaft and said rotatable vertical shaft for imparting rocking motion to the lifter shaft including drop feed mechanism for rendering the lifter shaft inactive.

2. The sewing machine defined by claim 1, in which said drop feed mechanism comprises an eccentric-clutch unit slidably mounted on said rotatable vertical shaft, a toothed rack slidably mounted to engage the eccentric-clutch for actuation by the eccentric portion thereof, a toothed

segment fixedly mounted on the lifter rock shaft and in mesh with the rack, a manually actuated fork engaging said clutch member for slidably moving the eccentric-clutch on said rotatable vertical shaft, and means on the rotatable shaft and said eccentric-clutch for imparting rotation to the eccentric-clutch.

3. A sewing machine comprising a bed plate, a feed dog movably mounted thereon, a rotatable vertical shaft, a feed dog lifter rock shaft, a feed rock shaft for imparting feed and return motion to the feed dog, means for imparting continuous rocking motion to said feed shaft, and operative connections between said rotatable vertical shaft and said lifter rock shaft for imparting rocking motion to the lifter shaft including drop feed mechanism for rendering the lifter shaft inactive, said drop feed mechanism comprising an eccentric-clutch unit slidably mounted on said rotatable vertical shaft, said unit having integrally formed cam and clutch members vertically spaced from each other, the clutch being concentric relatively to said rotatable vertical shaft, a slidably mounted toothed rack, a toothed segment fixedly mounted on the lifter rock shaft and in mesh with the rack, a manually actuated fork engaging said clutch for slidably moving the eccentric-clutch unit on said vertical shaft, a pin extending vertically from the clutch member for engaging the toothed rack when the unit is in raised position on the shaft, and a recess in the clutch member for engaging a protruding part of the vertical shaft when the eccentric-clutch unit is in lowered position on the shaft, whereby said unit is caused to rotate with the shaft.

4. A sewing machine comprising a bed plate, a feed dog movably mounted thereon, a rotatable vertical shaft, a feed dog lifter rock shaft, a feed rock shaft for imparting feed and return motion to the feed dog, means for imparting continuous rocking motion to said feed shaft, and operative connections between said rotatable vertical shaft and said lifter rock shaft for imparting rocking motion to the lifter shaft including drop feed mechanism for rendering the lifter shaft inactive, said drop feed mechanism comprising an eccentric-clutch unit slidably mounted on said rotatable vertical shaft, said unit having integrally formed cam and clutch members vertically spaced from each other, spaced apart ribs on the circumferential surface of the clutch member, the clutch being concentric relatively to said rotatable vertical shaft, a slidably mounted toothed rack, a toothed segment fixedly mounted on the lifter rock shaft and in mesh with the rack, a manually actuated fork provided with arms adapted to engage the clutch between said ribs for slidably moving the eccentric-clutch unit on said vertical shaft, means on the clutch member engaging the toothed rack when the unit is in raised position on the shaft, and means on the rotatable shaft and said clutch member for operatively connecting them and imparting rotation to the eccentric-clutch unit when the unit is in lowered position on the shaft.

5. A sewing machine comprising a bed plate, a feed dog movably mounted thereon, a rotatable vertical shaft, a feed dog lifter rock shaft, a feed rock shaft for imparting feed and return motion to the feed dog, means for imparting continuous rocking motion to said feed shaft, and operative connections between said rotatable vertical shaft and said lifter rock shaft for imparting rocking motion to the lifter shaft including drop feed mechanism for rendering the lifter shaft inactive,

said drop feed mechanism comprising an eccentric-clutch unit slidably mounted on said rotatable vertical shaft, said unit having integrally formed cam and clutch members vertically spaced from each other, a toothed rack slidably mounted to engage the eccentric-clutch for actuation by the eccentric portion thereof, a toothed segment fixedly mounted on the lifter rock shaft and in mesh with the rack, a manually actuated fork engaging said clutch member for slidably moving the eccentric-clutch on said vertical shaft, means on the rotatable shaft and on said eccentric-clutch unit for imparting rotation to the said unit, and a lever pivotally and adjustably mounted on a fixed part of the bed plate, having its free end bearing on the toothed rack and holding it in mesh with the teeth of the segment fixed to the lifter rock shaft.

6. A sewing machine comprising a bed plate, a feed dog movably mounted therein, a feed dog lifter rock shaft journaled under the bed plate and operatively connected to the feed dog, means for imparting rocking motion to said lifter shaft, a feed rock shaft parallel with the lifter shaft also journaled under the bed plate and operatively connected to the feed dog, and means for imparting continuous rocking motion to said feed shaft, said means for imparting rocking motion to said lifter shaft including drop feed mechanism for rendering the lifter shaft inactive, comprising a rotatable vertical shaft, an eccentric-clutch unit slidably mounted on said vertical shaft, a toothed rack slidably mounted under the bed plate and provided with an aperture between its toothed portion and slidable mounting for engaging the eccentric-clutch for actuation by the eccentric member thereof, a toothed segment fixedly mounted on the lifter rock shaft having its teeth in mesh with the teeth of the

5

rack, a manually actuated fork engaging said eccentric-clutch for slidably moving it up and down on said vertical shaft, and cooperating means on the vertical shaft and said eccentric-clutch unit for imparting rotation to the eccentric-clutch.

7. The sewing machine defined by claim 6, in which said eccentric-clutch unit comprises integrally formed cam and clutch members vertically spaced from each other, the clutch member being concentric relatively to the aforementioned rotatable vertical shaft on which the unit is slidably mounted, a pin extending vertically from the clutch member for engaging the toothed rack when the eccentric-clutch unit is in raised position on the shaft, and a recess in the clutch member for engaging a protruding part of the vertical shaft when the eccentric-clutch unit is in lowered position on the shaft, whereby said unit is caused to rotate with the shaft.

8. The sewing machine defined by claim 6, which includes a lever pivotally and adjustably mounted on a fixed part of the bed plate, having its free end bearing on the toothed rack and holding it in mesh with the teeth of the segment fixed to the lifter rock shaft.
